UNITED STATES PATENT OFFICE.

MARTIN HEINECKE, OF CARLINVILLE, ILLINOIS.

STRAW-STACKER.

SPECIFICATION forming part of Letters Patent No. 363,234, dated May 17, 1887.

Application filed February 10, 1887. Serial No. 227,169. (No model.)

To all whom it may concern:

Be it known that I, MARTIN HEINECKE, a citizen of the United States, residing at Carlinville, in the county of Macoupin and State of Illinois, have invented certain new and useful Improvements in Straw Stackers and Carriers; and I do hereby declare the following to be a full, clear, and exact description of the invention, such as will enable others skilled in the art to which it appertains to make and use the same.

My invention relates to improvements in straw stackers and carriers; and it consists, first, in constructing the frame of the truck in sections, whereby the front portions thereof may be raised, so as to permit the front wheels of the running-gear to readily turn; second, in the details of constructing the turn-table, as hereinafter set forth, and providing the same with a tripping device whereby the oscillating motion of the table is readily and with certainty maintained; third, in improved means for raising and lowering the carrier, as set forth; and, lastly, in the various details of construction and arrangement of parts, as hereinafter set forth, whereby a device easily operated, simple in construction, and economical and durable in character is made, all of which is fully illustrated in the accompanying drawings, in which—

Figure 1 represents a side view of a straw stacker and carrier embodying my invention. Fig. 2 represents a vertical longitudinal sectional view on line $\alpha\alpha$, Fig. 3. Fig. 3 represents a plan view of the tripping device and mechanism for operating the turn-table. Fig. 4 represents a sectional view on line yy , Fig. 3. Fig. 5 represents a bottom view of a portion of the turn-table, showing toothed wheels and rings having pins for operating the tripper. Fig. 6 represents a detail view of mechanism for operating the carrier.

Similar letters in the drawings refer to like parts.

The letter A represents the truck of the device suitably mounted on running-gears, and is composed of sectional parts $A'A^2$, one of which is higher than the other and securely fastened thereto. Suitably journaled in opposite sides of the section A^2 of the truck A is the shaft B, having mounted thereon the

band-wheel B', by which rotary motion is imparted to the same.

Mounted on the shaft B is a worm, B², which meshes with a worm gear-wheel, B³, rigidly mounted on a counter-shaft, C, which has bearings in cross-bars or portions of the truck. The shaft C carries on each end thereof a sprocket-wheel, C' C'.

The letters C² and C³ represent shafts running parallel to the shaft C, having bearings secured to the section A² of the truck A, and having sprocket-wheels C' C' on the outer ends thereof. The sprocket-wheels C' C' are properly connected to the sprocket-wheels C' C' by chains, so as to receive motion therefrom; but instead of these sprocket-wheels meshing gear-wheels may be used.

Mounted loosely on the shafts C² and C³ are gear-wheels C⁵ C⁶, which mesh with the toothed rim or wheel E² of the turn-table. The letters D' D' represent clutches mounted on the shafts C² and C³, so as to rotate therewith and slide thereon, and are connected by an arm-plate, D², having at its ends fingers which embrace the said clutches. These clutches are so arranged that only one can be in engagement with a wheel, C⁵, at one time, and when the device is not in operation both wheels may be free from the clutches. D is a turn-table, suitably mounted on the section A² of the truck A, and is formed of spokes E and a hub, E', and is provided on its under face with a toothed rim, E².

The letter E³, as shown in Fig. 2, represents supports, preferably of metal, having their lower ends secured to the section A² of the truck A, and provided on their inner faces with projections, forming shoulders E⁴, on which the outer edge of said rim E² rests. The upper end of each of these supports is bent inwardly, as at e, over the face of the rim of the turn-table, and thereby serving to keep the said turn-table in proper position during its oscillations.

On the under portion of the turn-table are curved or circular pieces or plates F F', having perforations F² therein. The plates F F' are arranged in concentric circles, and the perforations are adapted to contain pins F³, for a purpose hereinafter to be explained.

A tripper, G, consisting of a plate having

pins or studs G' projecting therefrom, is pivoted to a portion of the frame of the truck A , and connected to the tripper is a crank-arm, G^2 , (see Fig. 4,) having its other end pivoted to a rod, H , loosely connected to the plate D^2 by means of an arm, D^3 , of said plate, the said arm D^3 having an eye through which the said rod is passed, the rod having adjustable nuts H' on either side of the arm D^3 , so as to limit the movement of said rod and thereby the arm.

The letter J represents a spring secured to the rod J' , the said rod having its upper end secured to the pivotal connection of the crank-arm G^2 and the rod H , the lower end of said arm having a cross-bar and being guided in a bracket, J^2 , the said spring being between said cross-bar and upper end of the bracket J^2 , as shown in Fig. 4.

K is a bevel-wheel gearing with a bevel-wheel, K' , on a vertical shaft, K^2 , which shaft is journaled in bearings in the frame of the truck and passes through the center of the turn-table, the latter oscillating thereon. On the upper end of shaft K^2 is a bevel-wheel, K^3 , gearing with another bevel-wheel on shaft L , the latter shaft being journaled on one end in the frame of the elevating mechanism and on the other on the turn-table, and having at its outer end a sprocket-wheel, L' , which is connected by a chain to a double sprocket-wheel, L^2 , the latter journaled on the elevating-frame. A chain, L^3 , connects the wheel L^2 to another sprocket-wheel, L^4 , the latter being mounted on a shaft actuating the straw-carrier.

On the turn-table D is secured a frame, M , consisting of bars suitably secured together, as shown.

M' represents slanting or inclined bars having secured to their upper sides and at a small distance therefrom metallic bars M^2 , forming ways M^3 . Secured to the upper ends of the bars M' are iron bands or binding-pieces M^4 , having pulleys M^5 therein.

N is a shaft journaled in bracket-arms N' , secured to the frame M .

The letters P P denote arms pivoted or hinged to a rod, P' , which latter is secured at its ends to sides P^2 , operating in the ways M^3 .

To the slides P^2 are attached chains or cords, which pass over the pulleys M^5 and are secured to the shaft N , the said shaft having a crank-arm, N^2 , for operating the same, and thereby raising or lowering the said arms P P .

The carrier Q is composed of sections hinged together, and carries an endless apron or other suitable device for carrying the straw, all of which is old and well known. The said carrier is pivotally connected at or about the center of the sides thereof to the arm P , and it is also pivotally connected at its lower end to the arms Q' , which latter are pivotally secured to the inclined arms M' of the frame M .

At the end of the carrier to which the arms Q' are pivoted are attached cords S , connected to a shaft, Q^2 , mounted on the lower end of the

inclined arms M' , the said shaft Q^2 having a crank-arm by means of which the carrier when raised may be readily tilted forward and the front end lowered, as desired.

A rest, R , having its lower ends keyed or mortised to the axle of the running-gear, is firmly bolted to the truck A , the said rest being of use in sustaining one end of the carrier when the same is not in use.

The operation of the device is simple, and is as follows: Rotary motion having been imparted to the shaft B by means of the wheel B' , and thence by means of worm B^2 , wheel B^3 , shaft C , sprocket-wheels C' and C^2 to the shaft C^2 and one of the wheels C^5 , the turn-table is moved in one direction until the pin F^3 of one of the plates F' comes in contact with one of the studs of the tripper G , which causes the tripper to oscillate, thereby actuating, by means of the crank-arm G^2 , rod H , and the arm D^3 , the arm-plate D^2 , and thereby releasing the clutch on one of the shafts and throwing the other clutch on the other shaft into engagement with its wheel, whereby the motion of the turn-table is reversed. The spring J , which is compressed during the first portion of the movement of the arm-plate D^2 , aids in effecting the engagement of the clutch as soon as the tripper G carries the crank-arm beyond the vertical portion or dead-center of said spring, so as to release the same, thereby permitting it to exert its power in connection with the crank-arms.

The clutch being shifted, the motion of the turn-table is reversed, as is readily seen, the wheel C^5 , not in engagement with its clutch, running free upon its shaft. The operation of raising and lowering the carrier is readily understood from the description already given, and is as follows: The carrier being in position and formed of sections, as shown in Fig. 1, the same is raised by turning the crank-arm N^2 , and thereby, by means of the chains or ropes attached to the shaft N and the slides P^2 , which ride upward on the ways M^3 , the arms P P are raised, thereby lifting the forward end of the carrier, the rear end, Q' , remaining stationary, owing to the chains or ropes S . If desired to tilt the carrier forward, the shaft Q^2 is operated by means of the crank-handle Q^3 , whereby the chain or rope S is wound on its shaft, so that both the carrier is lowered and is tilted backward to be in proper position for carriage.

What I desire to claim and secure by Letters Patent is as follows:

1. In a straw-stack having a carrier, in combination with the frame M , having the inclined arms M' , the arms P , pivoted to said carrier and to slides P^2 , operating in ways M^3 , means, substantially as described, for raising and lowering said slides, and thereby the carrier and the chain S to the end of said carrier, and to a shaft mounted on the lower end of inclined arms M' , all of said parts combined substantially as shown and described, and for the purpose set forth.

2. In a straw stacker and carrier, the combination, with the truck A, having the section A² and the turn-table D, mounted thereon, consisting of the spokes E, hub E', and toothed rim E², of the perforated plates F F', having pins F³, said plates fastened to the spokes and arranged in concentric circles thereon, as shown and described, and for the purpose set forth.

3. The combination of the turn-table D, having toothed rim E², and plates F F', having pins F³, with wheels C⁵, gearing with said rim E², and clutches D', the connecting clutch-arm D², the tripper G, with studs G', and mechanism, substantially as described, intermediate of and connected to said tripper and clutch-arm for shifting said clutch-arm and reversing the motion of said turn-table, all substantially as described.

4. The turn-table D, having rim E², and plates F F', with pins F³, in combination with wheels C⁵ C⁶ on shafts C² C³, means, substantially as described, for rotating said shafts C² C³ in one direction, a tripper located in a path between said plates F F', and a clutch mechanism, substantially as described, actuated by said tripper for alternately engaging and disengaging said wheels C⁵ C⁶ from rigid connection with said shafts C² C³, all substantially as described.

5. The turn-table D, having toothed rim E², and plates F F', with means, substantially as described, secured thereto to actuate a tripping mechanism, in combination with the tripper G, having studs G', the crank-arm G², the pivoted rod H, the clutch-arm D², having arm D³, the shafts C² C³, the clutches D' D', and gear-wheels C⁵ C⁶, mounted on said shafts C² C³, as described, and mechanism, substantially as described, for rotating the said shafts C² C³ in

one direction, all substantially as and for the purpose set forth.

6. In a straw stacker and carrier, the combination of the shaft B, having band-pulley B' thereon, the worm B², mounted on said shaft B, the counter-shaft C, carrying worm-wheel 45 B³, meshing with the worm B² and wheels C' C', the shafts C² C³, parallel to shaft C, and having wheels C⁴ thereon, receiving motion from the said wheels C' C', the wheels C⁵, loosely mounted on the shafts C² and C³, and means, 50 substantially as described, whereby but one of said wheels C⁶ is rotated with either of said shafts C² C³, all substantially as and for the purpose set forth.

7. In a straw stacker and carrier, the frame M, with shaft N, mounted on the turn-table, in combination with the inclined bar M', the metallic bar M², forming, with the bar M', the ways M³, the bands M⁴, with pulleys M⁵, the carrier Q, having pivoted arms P, with slides 60 P², cords or chains connected to said slides P² and shaft N, and passing over pulleys M⁵, all substantially as and for the purpose set forth.

8. In a straw stacker and carrier, the carrier Q, having pivoted arms P, with slides P², the frame M, with inclined bars M' M², forming ways M³, means, substantially as described, for raising said slides P² in ways M³, and cords or chains S, attached to the end of the carrier Q and to shaft Q², all combined and operating 75 substantially as and for the purpose set forth.

In testimony whereof I affix my signature in presence of two witnesses.

MARTIN HEINECKE.
